UNITED STATES PATENT OFFICE.

EDGAR J. MOYER, OF INDIANAPOLIS, INDIANA.

VALVE-SEATING DEVICE.

Application filed January 11, 1923. Serial No. 611,981.

To all whom it may concern:

Be it known that I, EDGAR J. MOYER, a citizen of the United States, residing at Indianapolis, in the county of Marion and 5 State of Indiana, have invented new and useful Improvements in Valve-Seating Devices, of which the following is a specification.

This invention relates to improvements 10 in rocking or rotating cylinder valves for controlling the supply of hydro-carbon mixture to the explosion cylinders of internal combustion engines, and the object of the invention is to provide means for resisting the 15 tendency of the explosive force to lift the valve away from its seat and thereby cause leakage between the parts thus separated, with consequent loss in the amount of power developed by the engine.

20 Another object is to provide means for utilizing a part of the force of the explosion in the cylinder to thus hold the valve against its seat and prevent said leakage.

25 A further object is to apply the seating force to both ends of the valve alike in order to make the action equal and uniform for all parts of the valve.

30 I accomplish the above and other objects which will hereinafter appear, by the means illustrated in the accompanying drawings, in which—

Fig. 1, is a front elevation and partial section of the valve-end of an internal combustion engine cylinder showing the valve in 35 end elevation with my invention operatively applied. Fig. 2, is a side elevation of the same parts shown in Fig. 1. Fig. 3, is a top plan view of the same parts broken away in part. Fig. 4, is a view similar to that of

40 Fig. 1, showing a modified form in which a diaphragm instead of a piston actuates the lever for seating the rotary valve, and Fig. 5 shows a modification of the device of Fig. 4 whereby the parts are water-cooled.

45 Like characters of reference indicate like parts in the several views of the drawings.

During the compression and power strokes when the valve port of the engine is not registering with the working cylinder port, 50 power is lost by reason of the gases escaping through the cylinder port opening past the valve unless the valve is held to its seat. By holding the valve tightly against its seat adjacent the cylinder port opening the gases are prevented from escaping at those 55 places.

Referring to the drawings, a single explosion cylinder 6 is here shown by way of illustration, it being understood that this may be duplicated as many times as may be 60 desired, in accordance with the usual practice in gas engine construction. The hydro-carbon mixture admitted through a port 5 connects with a supply pipe 7 and the spent gases are discharged through the same port 65 to and out through a pipe 8. A valve here shown as a cylindrical valve 9, is rotated by means not shown, in a housing or seat 10 with which the pipes 7 and 8 communicate. The valve 9 is recessed at diametrically opposite portions as shown by dotted lines in 70 Fig. 1 in the manner to open the gas supply to the cylinder and later to appropriately open the cylinder to the discharge pipe. The valve may be rocked instead of 75 rotated, by well known changes in construction, without departing from the spirit of my invention.

The pressure of the expanding gases in 80 the cylinder 6 tends to move the valve away from port 5 and to cause leakage and loss of power. To correct this I exert a greater pressure against the valve to seat it than is exerted in the opposite direction from within the cylinder, as follows:—

85 Mounted in suitable journals cast on housing 10 is a rock-shaft 11 having a pair of lateral arms 4 extending from the ends of the rock-shaft, each of which is bifurcated to receive a roller 12 mounted in the bifurcated 90 ends and adapted to bear against the respective opposite ends of the valve 9 by appropriately rocking the shaft 11.

Keyed, or otherwise attached in fixed 95 manner to the shaft 11 is a bent lever 13, the opposite end of which from the rock-shaft is against a piston 14 that reciprocates in a small cylinder 15 formed in the explosion-end of the cylinder 6. The cylinder 15 communicates at its inner end with the explosion chamber of the much larger cylinder 6, and the outer end of its piston is against the lower end of the bent lever 13, as above 105 stated, with the result that when the charge in cylinder 6 is fired the explosion acting against piston 14 moves the latter out against the lever, and force is exerted through the lever, the rock-shaft and arms 4, against the valve 9, equally at both ends of the valve, but multiplied over the pressure 110 of piston 14 by the gain in leverage computed by taking the rock-shaft 11 as a ful-

crum, the lever 13 as a long arm and arms 4 as the short arm of a pivoted lever.

In the modification shown in Fig. 4 a diaphragm 16 crossing and closing the cylinder 15 bears against a pin 17 that contacts the lever 13. This is a substitute for the piston 14 of Fig. 1. In the modification in Fig. 5 a double diaphragm is used separated by a perforated sleeve 18 which is connected 10 with the jacket of the water-cooling system of the engine and thereby prevents the overheating of the device.

The pressure exerted on the valve by the piston or diaphragm through the associated 15 levers causes the rotating valve to be held tightly against its seat around the port opening to the large cylinder.

While I have here shown the best form of my invention now known to me, it is capable 20 of many changes in form and arrangement, some of which I have shown in the modified views, and I therefore do not desire to be limited unduly to the precise forms shown and described or any more than is 25 required by the appended claims, and having thus fully described my invention what I claim as new and wish to secure by Letters Patent, is—

1. The combination with a cylinder and a 30 valve housing on said cylinder having a cylinder port, of a cylindrical valve member rotatably carried in said valve housing, said valve member being unseated in part by the pressure in the cylinder through said cylinder port, of a lever adapted to press on one end of said valve member, a second lever adapted to press on the other end of said valve member, and means operated by the pressure in the cylinder for moving the said 40 levers in the direction to seat the valve member in opposition to said unseating tendency.

2. The combination with a cylinder and a valve housing having a cylinder port, of a 45 cylindrical valve member rotatably carried within said valve housing and of a diameter to provide oil clearance between the valve member and the wall of said housing, a lever contacting one end of said valve member at a point extended beyond said cylinder port, a second lever contacting the opposite end of said valve member at a point extended beyond the cylinder port, and means operated by the pressure in the cylinder 50 for moving said levers in the direction to seat said valve member in opposition to

the unseating tendency of the pressure in the cylinder through said cylinder port, said means permitting intermittent application and removal of pressure on said 60 valve ends.

3. The combination with a cylinder and a one piece valve housing having a cylindrical bore therethrough and a port into said cylinder, of a valve member rotatably carried 65 within and having a running fit in said housing permitting clearance for lubrication, a lever contacting one end of said valve member, said point of contact being on a section of the valve member projecting from the housing and beyond the cylinder port, a second lever contacting the opposite end of said valve member projecting from the housing and beyond the cylinder port, a pressure member adapted to be 70 actuated by pressure from the cylinder, and means interconnecting said levers and said pressure member whereby the travel of said pressure member is communicated to said levers thereby pressing the ends of said valve member to seat the valve on said cylinder port in opposition to the pressure from the cylinder through said port, and removing the pressure on the ends of the 75 valve member upon reduction of the pressure in the cylinder.

4. The combination with a cylinder and a valve housing having a cylinder port, of a cylindrical valve rotatably carried in said housing and having a diametrical clearance for the purpose of lubrication, a lever shaft, a lever secured to the shaft and adapted to contact the valve member at a point removed longitudinally of the valve from the cylinder port, a second lever secured to the shaft and adapted to contact the valve member at a point removed longitudinally of the valve from the opposite edge of said cylinder port, said points of contact being spaced apart a distance exceeding that of the cylinder port lying therebetween and being substantially diametrically opposite the cylinder port, an actuating lever of a length exceeding that of the first two levers and secured to said shaft, and a movable member adapted to be actuated by pressure within the cylinder, said movable member being adapted by reason of its travel thereby to contact said actuating lever.

Signed at Indianapolis, Indiana, this the 5th day of January, 1923.

EDGAR J. MOYER.
